US0D1049474S

(12) **United States Design Patent** (10) Patent No.: **US D1,049,474 S**
(45) Date of Patent: ** Oct. 29, 2024

(54) **ELECTRONIC CIGARETTE**

(71) Applicant: **BIDI VAPOR, LLC**, Grant-Valkarie, FL (US)

(72) Inventors: **Jiatai Chen**, Shenzhen (CN); **Shengwen Zhou**, Shenzhen (CN); **Jian He**, Shenzhen (CN)

(73) Assignee: **BIDI VAPOR, LLC**, Grant-Valkarie, FL (US)

(**) Term: **15 Years**

(21) Appl. No.: **29/874,262**

(22) Filed: **Apr. 17, 2023**

(51) LOC (14) Cl. **27-02**

(52) U.S. Cl.

USPC **D27/162**

(58) **Field of Classification Search**

USPC D27/162, 100, 101, 141, 163–165, 172, D27/174–176, 183, 185–194; D23/366; D24/110, 110.5

CPC A24F 40/00; A24F 40/10; A24F 40/40; A24F 40/90; A24F 40/95; A61M 15/00; A61M 15/06
